UNITED STATES PATENT OFFICE.

JAMES WILSON, OF MERRITTON, CANADA.

WIRE-ROPE MACHINE.

SPECIFICATION forming part of Letters Patent No. 447,392, dated March 3, 1891.

Application filed June 16, 1890. Serial No. 355,686. (No model.) Patented in Canada February 10, 1890, No. 33,644.

To all whom it may concern:

Be it known that I, JAMES WILSON, a citizen of Canada, residing at Merritton, in the county of Lincoln, in the Province of Ontario, Canada, have invented a new and useful Wire-Rope Machine, (for which I have obtained a patent in Canada, No. 33,644, bearing date February 10, 1890,) of which the following is a specification.

10 My invention relates to improvements in wire-rope machines, its essential parts being a rotary face-plate having round apertures to allow the traversing of wire or strand through the same in conjunction with a wire-guide, also apertured, having a conical projection and an adjustable die, and a second face-plate, also apertured, all held in position and supported by two or more longitudinal rods connected to the same; and the objects of my

15 improvements are, first, to produce a seven wire or strand cable or wire rope having a center core of a flexible and ductile nature; second, to afford facilities for the proper adjustment of the guide and die for different sizes of wire or strands without displacing the machine or parts thereof in general, and, third, to provide means to allow twelve independent wires or strands to coil around the seven-wire strand, thus producing a nineteen-wire

20 strand, cable, or rope, this including the center wire or core. I attain these objects by the mechanism illustrated in the accompanying drawings, in which—

Figure 1 is a sectional view of a broad side 35 of the machine. Fig. 2 is an end elevation of the first apertured face-plate. Fig. 3 is an end elevation of the adjustable apertured guide and the support therefor and apertured cone having a rounded nose. Fig. 4 is an end 40 elevation of the adjustable support and steadyng-bearing for the adjustment of different center dies; and Fig. 5 is an end elevation of the second apertured face-plate with an attached cone having a rounded nose and 45 apertured to allow a seven-strand wire to pass through the same.

Similar letters refer to similar parts throughout the several views.

In the drawings, A is the first face-plate, and 50 its center hole *a* is bored to admit a hollow drive-shaft, which rotates the machine and allows the passage through the same of a core

or center wire to form the center core of the cable.

B B are two longitudinal rods having a collar and nut at each end, the whole structure being supported by the said plate and rods.

The adjustable wire-guide support C and the die D in its support D' are capable of sliding on the rods to suitable positions as 60 the varying degrees and caliber of wire necessitate, and are held by set-screws T to the said rods. This die D, which is in halves, is provided with flanges at each end to maintain its longitudinal position, and it is also 65 held in position in its support D' by means of its cap D', which is screwed or bolted to the said support D'. The face-plate E is secured to the right-hand end of the said rods by means of the collars *x* and nuts Y, the same 70 as the face-plate A, as shown.

The cone F is secured to the center of the support C by means of its flange J' and set-screws K, and the conical projection M is secured to the center of the plate E by means 75 of the screws N', which screw into the flange of the same. The whole of this machine as described, when in operation, revolves on and with the hollow shaft, as before mentioned.

The center wire is designated by H and 80 passes through the said shaft in the center of the plate A, then through the tapered aperture of the cone F. At this juncture the six wires designated by I pass through the six apertures *i* in the plate A, then through the 85 six apertures J in flange J' of said cone and engage with the center wire and coil around the same in close proximity to the rounded nose of the said cone. The seven wires then pass through the die D, which smoothes the 90 same, and on through the aperture of the cone M, thus producing a seven-wire rope H'. In the construction of a nineteen-wire cable twelve wires (designated O) pass through the twelve apertures P in the plate A and along 95 longitudinally to and through the twelve apertures S of the plate E and over and around the projecting cone M, to engage with and coil around the seven-wire rope H' in close proximity to the rounded nose N of the said cone 100 M, thus forming a nineteen-wire rope or cable, (designated by H².)

It will readily be perceived that a seven-wire cable may be made independent of the

extra twelve wires, the machine working in complete order without them.

To vary the caliber of the cable, stronger wire or strands of wire may be effectually used or a stronger center core composed of tarred hemp or other suitable material.

The machine is supplied with wire from eighteen spools, (not shown,) each on a frame of its own and all attached to a plate which revolves on and with the said hollow shaft at any required distance from the machine.

The wire cable is received from the machine by a grooved cone, (not shown,) which revolves away from the end of the machine and at a required and suitable rate of speed.

What I claim as my invention, and desire to secure by Letters Patent, is—

1. The combination, in a wire-rope-strand machine, of a rotary face-plate A, having a series of apertures P and *i* and a bored center *a*, the longitudinal rods B B, the adjustable

support C, provided with a hollow cone F, with its flange J', having apertures J and set-screws K, the removable die D, cap D², and adjustable support D', arranged and devised substantially as described and set forth.

2. In a compound wire-rope-strand machine, a rotary face-plate A, having a series of apertures P and *i* and center *a*, the support C, provided with hollow cone F, with flange J', having apertures J and set-screws K, the support D', with its die D and cap D², in combination with the plate E, having apertures S, and a hollow flanged cone M, with rounded nose N, held in position by the screws N', all substantially combined by the longitudinal rods B B, substantially as specified and set forth.

JAMES WILSON.
